UNITED STATES PATENT OFFICE.

EDGAR HOLGER HANS JØRGENSEN, OF ELSINORE, DENMARK.

COCK, VALVE, AND THE LIKE.

Application filed December 28, 1927, Serial No. 242,191, and in Denmark January 17, 1927.

The invention relates to improvements in locks designed primarily for valves of the plug type.

The principal object of the invention is to provide a new and improved connection between the stem of the valve plug and a removable key for turning said stem, the construction being such that the key cannot accidentally fall from the lock whether the latter be open or closed.

Another object is to provide a special stopping device to prevent the removal of the key from the lock when the cock or valve is open and only when the cock or valve is closed is it possible to remove the key from the lock.

This arrangement is very practical in cocks and valves that are used for inflammable liquids, poisonous gases and the like as it gives a security that the cock or valve be completely closed when the key is removed from the lock. Simultaneously the cock or valve is locked, and can only be opened by means of the key particularly belonging to it.

With the foregoing in view, the invention resides in the novel subject matter herein-after described and claimed, the description being supplemented by the accompanying drawing.

Fig. 1 is a vertical sectional view through a cock housing and the lock mechanism, parallel with the boring of the cock housing,

Fig. 2 shows a vertical section at right angles to Fig. 1,

Fig. 3 shows the lock and cock seen from above,

Fig. 4 is a sectional view on line A—A of Fig. 2, and

Fig. 5 is a view similar to a portion of Fig. 1 showing a different form of construction.

In the drawing above briefly described, the numeral 1 designates the usual cock housing formed with a branch 2 at its top.

45 A sleeve 3 is secured to the branch 2 by any suitable means. This sleeve 3 forms a guide for the key 4 and covers the stem of the cock plug 5. This stem of the cock plug 5 has a cylindrical part 6 one side of which has a flat surface 7, a cylindrical neck 8 of a somewhat smaller diameter than the part 6, and a cylindrical part 9 of the same diameter as the part 6, and likewise having a flat surface 10, arranged opposite the flat surface 7.

55 Within the lower end of the sleeve 3 there is placed around the stem 6 an annular tum-

bler 11 the inner side of which has a straight edge 12 that fits the stem 6 by which the tumbler is forced to accompany the rotation of the cock plug 5. On the outer side of the 60 tumbler 11 are projections 13 that engage notches 14 in the inner end of the sleeve 3 for stopping the tumbler. This tumbler 11 is held in engagement by means of a compression spring 16 and thus the cock plug 5 is 65 locked.

The key 4 has a bore that fits the neck of the cock plug 5, and within the key 4 there is a segment-shaped bit 17 that fits the flat surfaces 7 and 10, allowing the cock plug 5 to 70 be turned by means of the key 4. When the key 4 is inserted in the lock the bit 17 is pushed down along the flat surface 10 of the stem to the neck 8 which is smaller in diameter than the parts 6 and 9 so that the key 4 75 can be turned around the neck until the bit 17 is above the flat surface 7, whereupon the key may be pushed down to the tumbler 11. By overcoming the action of the spring 16 the key is used to push the tumbler 11 out 80 of engagement with the notches 14 after which the cock plug 5 can be turned by means of the key 4. Because of the shape of the cock plug stem the lock can practically only be opened with the key particularly fitted to said stem. Furthermore, the key cannot be pushed quite out of the lock by the action of the spring 16 when the tumbler is pushed into engagement, nor can said key accidentally fall from the lock as it 90 must first be turned a half revolution around the neck 8 of the cock plug, before it can be removed from the lock.

On the handle 18 of the key 4 there is a pin 19 which underlies an arcuate flange 20 95 on the sleeve 3 when the key is pressed down and turned to open the cock plug 5 whereby the removal of the key is prevented when the cock is open. When the key is turned back so that the cock is closed, the spring 16 will automatically push the tumbler 11 100 into engagement and lock the cock while the key is simultaneously pushed a corresponding distance out of the lock, at which time its handle 18 abuts the ends of the flange 20. 105 Chance blows against the handle of the key can thus not cause any rotation of the cock plug, and as a further precaution the key may be removed from the lock.

To prevent the lifting of the cock plug 5 110 when removing the key which would otherwise cause the lock to leak, the housing may

be provided with a specially formed edge 21 within the branch 2. After inserting the plug in the housing 1 this edge 21 is bent in over a suitably arranged projection 22 which holds the plug in position.

In Fig. 5 a somewhat different form of construction is employed, the screw 23 being substituted for the edge 21, said screw abutting a bevel 24 formed upon the top of the 10 cock plug 5.

As excellent results are obtainable from the details disclosed, they are preferably followed. However, within the scope of the 15 invention as claimed, variations may be made.

I claim:

1. A lock comprising a stationary sleeve, a rotatable stem disposed within said sleeve and spaced therefrom, said stem having an outer and an inner cylindrical part, and a neck joining said parts, said parts having flat longitudinal surfaces arranged out of alinement with each other, a spring-applied 20 tumbler around said stem slidable but non-rotatable thereon, inter-engaging means on 25

said tumbler and said sleeve for holding said tumbler normally against rotation, and a tubular stem-turning key insertible into said sleeve around said stem, said key having an internal projection adapted to slide 30 inwardly on the flat surface of said outer stem part, turn around said neck and then slide inwardly on the flat surface of said inner stem part, said tumbler being releasable by maximum inward movement of said key. 35

A lock comprising a stationary sleeve, an arcuate flange on said sleeve, a rotatable stem disposed within said sleeve, a spring-pressed tumbler for locking said stem, and a stem-turning key insertible into said sleeve, 40 said key having a handle adapted to abut the ends of said flange when said tumbler is in operative position, and a pin on said handle capable of lying against the inner side of said flange when said key is forced inwardly to release said tumbler and then turned. 45

In testimony whereof I have hereunto affixed my signature.
